PRUNING SHEARS

Edward Albert Rogers, London, England, assignor to
Wilkinson Sword Limited, London, England, a company of Great Britain

Filed Aug. 31, 1961, Ser. No. 66,559

Term of patent 14 years

(Cl. D22—4)

FIG. 1

FIG. 2

FIGURE 1 is an elevational view of a pair of pruning shears showing my new design;

FIGURE 2 is a view of the opposite side thereof;

FIGURE 3 is a view taken from the right side of FIGURE 1;

FIGURE 4 is a similar view taken from the left side of FIGURE 1;

FIGURE 5 is a fragmentary view similar to FIGURE 1 with the jaws in open position.

I claim:
The ornamental design for pruning shears, as shown.
